CLAIM

The ornamental design for a dispenser, as shown and described.

DESCRIPTION

FIG. 1 is a top plan view of a dispenser showing our new design;

FIG. 2 is a bottom plan view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a front isometric view thereof; and,

FIG. 8 is a rear isometric view thereof.

The evenly broken lines are shown for the purpose of illustrating parts of the article that form no part of the claim. The interior surfaces of the article as shown in FIGS. 1, 4, 7, and 8 form no part of the claim.

1 Claim, 8 Drawing Sheets
